W. E. PHELPS.

METHOD AND APPARATUS FOR PRODUCING PAPER STOCK,
APPLICATION FILED JUNE 26, 1913.

1,123,000.

Patented Dec. 29, 1914.

UNITED STATES PATENT OFFICE.

WILLIAM E. PHELPS, OF BALTIMORE, MARYLAND.

METHOD AND APPARATUS FOR PRODUCING PAPER-STOCK.

1,123,000.

Specification of Letters Patent.

Patented Dec. 29, 1914.

Application filed June 26, 1913. Serial No. 775,858.

To all whom it may concern:

Be it known that I, WILLIAM E. PHELPS, a citizen of the United States, residing at Baltimore, in the State of Maryland, have 5 invented certain new and useful Improvements in Methods and Apparatus for Producing Paper-Stock, of which the following is a specification.

This invention relates to an improvement 10 in the art of disintegrating the fibers of paper making material, preparatory to further steps with the same material in the process of manufacturing paper.

My improvement contemplates the disintegration of fibers both of old paper and fibers of chemically treated wood and other vegetable fibers.

The object of this invention is to provide a combination of steps that constitute a new 20 method; first to provide for a circulation through conduits, of an aqueous solution of the paper stock fibrous material while the process of disintegrating the fibers is going on; second, to arrange the conduit 25 through which the solution of fibrous material must circulate so there will be formed a plural number of consecutive sections of conduit each section to be separated from the others but the several sections to be connected, in order that the 30 solution of fibrous material will have a continuous flow through said consecutive sections; and third, to apply to each succeeding section of conduit an independent suction 35 or partial vacuum draft that shall be greater than that applied to the preceding section, whereby as the solution of fibrous material progresses through the conduit the disintegration of the fibers will be facilitated and 40 hastened.

The accompanying drawing serves to elucidate the improved method which will now be described.

The drawing shows an elevation of the 45 apparatus.

An upright cylindric tank, 1, shown with its side partly broken away, has a tapered or hopper-shaped bottom, 2, and is suitably supported. A vertical shaft, 3, is mounted 50 within the tank on a step, 4, and said shaft has arms, 5, that are carried around as the shaft turns; the inner wall of the tank is

provided with arms, 6, that project toward the said vertical shaft, and these arms are so positioned as to avoid being struck by 55 the moving arms of the shaft. The top of the tank is closed by a head or cover and has a removable cap-plate, 7, through which old paper or other fiber material and also any chemical desired may be supplied into 60 the tank. A pipe, 8, opens through the side of the tank and has two branches each provided with a valve, whereby both or either water and steam may be entered into the tank so as to produce with the fibrous ma- 65 terial an aqueous solution having the tem- perature desired. The bottom of the tank has a suitable draw-off gate or valve, 9.

A horizontal shaft, 10, is mounted in suitable hanger bearings, and bevel gears, 70 11, connect this shaft with the said vertical shaft, 3, in the tank. Any suitable power may be used to impart motion; for the purpose of illustration a motor, 12, is shown, and a drive-belt, 13, passes over a pulley, 14, 75 on the motor shaft and also over a pulley, 15, on the horizontal shaft, 10. A plural number of sections of conduit pipes are employed to make up the circuit from the bottom of the tank, 1, to the top of the same 80 tank; and a plural number of rotary or centrifugal pumps are also employed to produce a suction or vacuum draft from one section of conduit and discharge into the next succeeding section of the conduit. The 85 first section, 16, of the conduit leads from the bottom of the tank 1, to the first rotary pump, 17; the second section, 18, is separate from the first section, and leads from the said first pump to the second pump, 19. The 90 second pump, 19, is larger than the first pump, 17, and in operation, therefore, applies a suction or draft on the solution of fibrous material in the second section of the conduit greater than that which was applied 95 by the first pump, 17, consequently a partial vacuum is created in the second section, 18, of the conduit. The third section, 20, of the conduit is separate from the second section, 18, and leads from the second pump, 19, to the third pump, 21. This third pump is larger than the second pump and applies a suction or draft on the solution of fibrous material in the third section of the conduit

still greater than that which was applied by the second pump, 19, and thereby a partial vacuum is created in the third section, 20, of the conduit. The final section comprises two parts, 22, 23, of the conduit and in the present instance leads from the third pump, 21, to the top of the tank, 1. For the purpose of illustration four sections of conduit and three pumps are shown but 10 any other plural number may be used.

A by-pass section, 24, of conduit is shown that leads from the second pump, 19, direct to the last part, 23, of the final section; thus cutting out the third section, 20, and 15 the third pump, 21. In order to use this by-pass section, a cut-off valve, 25, is provided in the third section, 20, of the conduit, and also a cut-off valve, 26, is provided at the point that defines the separation of the 20 two parts, 22, 23, of the fourth section of conduit. The by-pass section, 24, itself is provided with a cut-off valve, 27.

The word "conduit" as herein used is intended to have the same meaning as the 25 word "pipe."

The pumps may be driven in any suitable way and by any desired power; in the present instance the pumps are shown to be driven from the horizontal shaft, 10. A 30 belt, 28, over suitable pulleys drives the first pump, 17; a belt, 29, drives the second pump, 19, and a belt, 30, drives the third pump, 21.

From this description and the apparatus 35 shown, it will be understood that the aqueous solution of fibrous material flows from the bottom of the tank through a conduit or pipe that comprises a plural number of consecutive sections each of which is 40 separated from the adjoining sections by a pump, and that an independent suction or partial vacuum draft is separately applied to each conduit section, and that a greater suction or draft is applied to each succeeding 45 section than that applied to any of the preceding sections and finally the flow of the solution may be returned to the tank. By this method the fibrous material will be suspended in the aqueous solution as the 50 material and solution both move through the conduit, and their flow through said conduit will be relatively retarded at a plural number of points at each of which a suction-pump is located, and a partial vacuum draft will be produced in the several 55 sections of the conduit intermediate such points.

The effect of applying at different points of the conduit a suction or draft to the solution of water and suspended fibrous material as it flows through the conduit, so that as the solution progresses the partial vacuum produced will be increased by each pump, may be accomplished either by hav-

ing the succeeding pumps of gradually increased size, as here shown, or if all the pumps be of the same size, by having the speed of operation of each one of the succeeding pumps after the first, greater than that applied to the preceding pump. 70

Having thus described my invention what I claim and desire to secure by Letters Patent is:—

1. The improvement in the art of disintegrating fibrous paper-making material, 75 which consists of forming an aqueous solution in which the fibrous material is suspended; moving the solution and said fibrous material through a conduit wherein in their flow is relatively retarded at a plural number of points, and producing a partial vacuum draft in the several parts of the conduit intermediate such points.

2. The improvement in the art of disintegrating fibrous paper-making material 85 which consists of forming an aqueous solution of the fibrous material; moving the aqueous solution with the fibrous material suspended therein through a conduit; applying at a plural number of points along 90 such conduit a suction to produce within the conduit a partial vacuum draft at each point—the suction applied at each succeeding point being greater than that applied at the last preceding point. 95

3. The improvement in the art of disintegrating fibrous material which consists of forming an aqueous solution of the fibrous material in a tank; circulating the said solution through a conduit that leads from 100 the tank; and applying at a plural number of points along such conduit a suction to produce within the conduit a partial vacuum at each point—the suction applied at each succeeding point in the conduit being 105 greater than that applied at the last preceding point.

4. An apparatus for disintegrating fibrous material having in combination a tank to contain an aqueous solution of the fibrous 110 material; a conduit leading from said tank and making a circuit back to the tank and said conduit forming a plural number of consecutive conduit sections; and a vacuum-producing pump separating every two adjoining sections and each pump producing a partial vacuum draft in the conduit section 115 next preceding the pump.

5. An apparatus for disintegrating fibrous material having in combination, a tank to 120 contain an aqueous solution of the fibrous material; a conduit leading from said tank and through which the solution and material will flow and said conduit forming a plural number of consecutive sections; and a plural number of vacuum-producing pumps along the line of the said conduit 125 each succeeding pump having a greater

capacity to produce a partial vacuum than the last preceding pump.

6. An apparatus for disintegrating fibrous material having in combination, a tank to contain an aqueous solution of the fibrous material; a conduit leading from said tank and forming a plural number of consecutive sections; and a plural number of vacuum-producing pumps each pump connecting the

terminal end of one conduit section with the initial end of the next succeeding section.

In testimony whereof I affix my signature in presence of two witnesses.

WILLIAM E. PHELPS.
